UNITED STATES PATENT OFFICE.

CHARLES S. HILL, OF BOSTON, MASSACHUSETTS.

PIECED SOLE.

1,401,981.

Specification of Letters Patent.

Patented Jan. 3, 1922.

Application filed May 21, 1919. Serial No. 298,737.

To all whom it may concern:

Be it known that I, CHARLES S. HILL, a citizen of the United States, residing at Boston, in the county of Suffolk and State 5 of Massachusetts, have invented new and useful Improvements in Pieced Soles, of which the following is a specification.

This invention relates to a sole composed of a forepart section and a rear section, 10 the sections being united at the shank portion of the sole.

One object of the invention is to provide a strong and durable connection between the sections, the only evidence of which visible 15 at the outer side of the sole, is a butt joint extending across the shank portion.

Another object of the invention is to provide a pieced sole, the rear section of which is composed of a plurality of relatively thin 20 layers, and adapted to be manufactured at a relatively small expense, and to be securely connected with a forepart section having suitable wearing qualities, and composed, for example, of sole leather.

25 To these and other related ends, the invention consists in the improvements which I will now proceed to describe and claim.

Of the accompanying drawings forming a 30 part of this specification,—

Figure 1 is a view of the bottom or tread side of a sole embodying the invention.

Figure 2 is a view of the opposite side of the sole.

Figure 3 is a fragmentary sectional view 35 showing the rear end portion of the forepart section.

Figure 3^a is a view similar to Figure 3, showing a modification.

Figure 4 is a fragmentary sectional view, 40 showing parts of the two sole sections before they are united.

Figure 5 is a fragmentary sectional view, showing parts of the two sole sections after 45 they are united, and before the fastenings hereinafter described are concealed at the outer face of the sole.

Figure 6 is a section on line 6—6 of Figure 2.

Figure 7 is a view similar to Figure 6, 50 showing a modification.

Figure 8 is a view similar to Figure 6, showing another modification.

The same reference characters indicate the same parts in all of the figures.

In the drawings, 12 represents the forepart section of a sole, this section being preferably a single piece of sole leather, as indicated by Figure 3, although, if desired, the forepart section may be composed of a relatively thick body layer 12^a of sole leather 55 or the like, and a thinner layer 12^b.

The rear end portion of the section 12 is formed by spaced apart outer and inner tongues 13 and 14, the section being preferably split, as indicated at 15, to form the inner side of the tongue 13. The inner tongue 14 is spaced from the outer tongue either by the removal of some of the material, or by compression of the material to form a surface indicated by the dotted line 16 60 (Figure 3), said surface being the outer side of the tongue 14. The inner side of the section 12 is preferably rebated to further reduce the thickness of the tongue 14 and form a shoulder 17 at the base of the tongue. 65 When the section is constructed as shown by Figure 3, the shoulder 17 is formed by one end of the layer 12^b.

The tongues 13 and 14 are provided respectively with end faces 17 and 18, which 70 are perpendicular to the sides of the section and are preferably in the same plane.

The forepart section includes the tread portion and a part of the shank portion of the sole. The rear section next described 80 includes the heel and a part of the shank portion of the sole, said rear section being indicated as a whole by the reference numeral 19. The rear section is provided with outer and inner end faces 22 and 23, which 85 abut against the end faces 17 and 18 of the forepart section, and form outer and inner butt joints, indicated at 20 and 21 in Figures 6 and 7, the outer butt joint 20 being on the outer or tread face of the sole. The rear 90 section is provided with outer and inner tongues 24 and 25, projecting from the end faces 22 and 23, and alternating with the tongues of the forepart section.

The rear section 19 is preferably composed 95 of a plurality of layers, which may be of any suitable material, such as split leather, or skivings, or other material suitable for the purpose. Said layers are of different lengths, there being a shorter layer 19^a interposed between two longer layers 19^b. 100 The inner end face 23 of the rear section is formed by the forward end of the shorter

layer 19^a. The outer end face 22 is formed by the end of a single layer 19^e which forms the outer face of the rear section.

- I prefer first, to assemble all the layers 5 of the heel section, excepting the layer 19^e, and then engage the rear section with the forepart section, as indicated by Figure 5, the outer tongue 13 of the forepart section being turned back. The tongues 24 and 25 10 of the rear section may be cemented to the inner tongue 14 of the forepart section, and are preferably additionally united to said inner tongue by fastenings extending through each of the tongues, said fastenings 15 being preferably stitches 27. After the fastenings are in place, the outer tongue 13 is turned down and cemented to the adjacent tongue 24 to form the outer butt joint 20 and conceal the fastenings 27.
- 20 I prefer to unite all the layers of the heel section, excepting the outer layer 19^e, by similar fastenings 27^a, inserted before the outer layer 19^e is applied. The application of the layer 19^e completes the outer butt joint 20 and covers the fastenings 27^a. The outer layer 19^e is preferably secured in place by cement.

It will now be seen that the two sections are firmly united in such manner that there 30 is no evidence of the pieced construction at the outer face of the sole, excepting the butt joint 20. Owing to the fact that the end faces forming this butt joint are perpendicular to the side faces of the sole, the joint 35 is durable and not liable to be opened by wear. The laminated construction of the rear section enables the latter to be made of relatively inexpensive material or materials, and yet possess sufficient strength and durability.

Figure 7 shows a modification, in which the rear section is made in a single piece, instead of being laminated, the tongues 24 being integral with the body of the rear section. 45 In this case the rear section may be made of a quality of leather or other material which is cheaper than that of which the forepart section is composed.

The rear section 19 may be composed of 50 two layers 19^d and 19^e, as shown by Figure 8. The forward end of the longer layer 19^e forms an inner tongue 25^a. The outer tongue 24^a is formed by a separate piece bearing on an inwardly offset seat on the layer 19^d, and is covered by a tongue 30 which is integral with the layer 19^d.

It will be seen that the forepart section has a solid wear-sustaining portion, which includes the tread face, and is of greater 60 thickness than either of the layers of the rear section. When the forepart section is made in one piece, the thickness of its solid wear-sustaining portion exceeds the aggregate thickness of the layer 19^a and the two 65 layers 19^b. When the forepart section is

made in two pieces, as shown by Figure 3^a, the thickness of its solid wear-sustaining portion exceeds the aggregate thickness of the layer 19^a and one of the layers 19^b. When the rear section is composed of two layers, as 70 shown by Figure 8, the solid portion of the forepart section is thicker than either of said layers.

It will be understood that when the sole is incorporated in a shoe, the rear section is 75 raised by the curvature of the sole above the tread face of the forepart section, no wear being sustained by the rear section, so that the rear section may be made up of layers of relatively cheap material, without de- 80 tracting from the durability of the sole, the operation of assembling said layers producing the abutting faces 22 and 23, and the tongues 24 and 25.

I claim:

1. A pieced sole composed of a fore part section having a rear portion formed by spaced apart rearwardly projecting outer and inner tongues, the outer ends of said tongues forming end faces substantially 90 perpendicular to the tread face of the section, the outer tongue being flush with the tread face and spaced from the inner tongue, while the inner tongue is offset from the top face by a shoulder 17; and a rear 95 section having outer and inner end faces at its forward end portion, the said outer end face abutting the outer end face of the fore part section to form an outer butt joint on the tread face of the sole, the said inner 100 end face abutting the inner end face of the fore part section to form a concealed inner butt joint, the rear section being provided with tongues bridging said joints, and alternating with the tongues of the fore part section, one of the rear section tongues abutting the shoulder 17 to form a butt joint on the top face of the sole.

2. A pieced sole substantially as specified by claim 1, the tongues of the rear section 110 being united to the inner tongue of the forepart section by fastenings which are concealed by the outer tongue of the forepart section.

3. A pieced sole comprising a solid forepart section having a rear end portion formed by spaced apart outer and inner tongues integral with the section, and having end faces perpendicular to the sides of the section, the outer tongue being an extension of the outer or tread face of the section, and a rear section composed of a plurality of shorter layers, having end faces abutted against the end faces of said tongues to form outer and inner butt joints, and a 120 plurality of longer layers forming tongues bridging said joints and alternating with the tongues of the forepart section.

4. A pieced sole substantially as specified by claim 3, having fastenings uniting the 130

85

100

105

115

120

125

tongues of the rear section to the inner tongue of the forepart section and concealed by the outer tongue of the latter.

5. A pieced sole substantially as specified by claim 3, having fastenings uniting the tongues of the rear section to the tongues of the forepart section, and fastenings uniting

all the layers of the rear section excepting the outer layer, and concealed by said outer layer.

10 In testimony whereof I have affixed my signature.

CHARLES S. HILL.
